COMBINED DUAL TAIL PIPE AND LICENSE BRACKET FOR BICYCLES

Wilfred Williams, Toledo, Ohio, assignor to Midwest
Stamping & Manufacturing Company, Bowling Green,
Ohio, a corporation of Ohio

Application March 7, 1955, Serial No. 34,909

Term of patent 7 years

(Cl. D90—1)

Figure 1 is a perspective view of the combined dual tail pipe and license bracket for bicycles, showing my new design;

The fragmentary dotted line disclosure of a bicycle is shown only for purposes of illustration.

I claim:

The ornamental design for combined dual tail pipe and license bracket for bicycles, as shown and described.
